LOCOMOTIVE STOKER

Nathan M. Lower, Crestwood, N. Y., assignor to
The Standard Stoker Company, Incorporated,
a corporation of Delaware

Application May 2, 1930, Serial No. 449,331
Renewed September 20, 1934

14 Claims. (Cl. 198—15)

This invention pertains to mechanical locomotive stokers and has for one of its objects the improvement in the construction of the portion of a stoker between the locomotive and tender.

In present locomotive stoker constructions wherein the stoker comprises a trough rigidly mounted on the tender and an elevator conduit rigidly mounted on the locomotive, the trough and elevator conduit are both universally jointed to a flexible intermediate conduit, and in order to transfer fuel through the stoker a plurality of conveyor screws are connected by a series of universal joints. The coal is greatly pulverized by the rotating of these universal joints with the result that a large amount of the fuel is drawn through the locomotive stack unburned. It is a further object of this invention to construct such a stoker; that is, one having a fixed trough, a fixed elevator conduit and a flexible intermediate conduit, so as to eliminate the universal joints between the conveyor screws, in order that a relatively coarser grade of coal will be delivered to the locomotive firebox, thus obtaining more economical firing.

Another object of my invention is to mount the stoker engine in a novel location where there is ample space to facilitate repairing.

Other objects, advantages and novel details of construction will be apparent during the course of the following description and appended claims taken in connection with the accompanying drawings, in which:

Fig. 1 is a vertical longitudinal sectional view of a portion of a locomotive and tender with the invention shown in elevation applied thereon, and having parts thereof broken away.

Fig. 2 is a vertical sectional view of the rear end of the conveyor trough or transfer conduit and illustrates the gearing.

Fig. 3 is a part sectional view showing the stoker engine mounting in detail.

Fig. 4 is a vertical sectional view of a portion of the locomotive and tender and illustrates the construction of the stoker between the locomotive and tender.

Fig. 5 is a sectional view taken on line 5—5 of Fig. 4, showing the relationship of the stoker parts when the locomotive and tender are on a straight track.

Fig. 6 is a sectional view, similar to Fig. 5, illustrating the relationship of the stoker parts when the locomotive and tender are on a curved track.

Fig. 7 is a sectional view taken on line 7—7 of Fig. 1.

Fig. 8 is a sectional view taken on line 8—8 of Fig. 4.

Fig. 9 is a sectional view taken on line 9—9 of Fig. 1.

In Figure 1, the numeral 1 designates the locomotive; 2, the firebox; 3, the firing opening; 4, the grates; 5, the cab; 6, the locomotive frame; 7, the tender; 8, the coal bunker; and 9, the water storage compartment. The stoker comprises four main units or conduits, namely; the conveyor trough or transfer conduit 10, which is rigidly mounted in the tender; an elevator conduit 11, which is rigidly mounted on the locomotive; an intermediate conduit or spout, which makes communication between the transfer conduit 10 and the elevator conduit 11; and the horizontal firedoor conduit 60.

The transfer conduit 10 is mounted in the tender to form a portion of the surface of the water compartment 9. The outwardly extending flange 13 at the top of the transfer conduit and the outwardly extending flange 14 at the front of the transfer conduit are secured to the tender deck 15 and front sheet 16 respectively, making water-tight joints. A conveyor screw 17 extends the full length of the transfer conduit and into the rear portion of the spout 12. It is driven at its rear end through gearing in the gear case 18 by the engine 19. Heretofore, stoker driving engines have been mounted beneath the locomotive deck or beneath the tender deck and there is not ample space around the engine to permit ready repairing, "piping up", mounting, etc. For this reason I have positioned the engine 19 on the top of the tender and provided an inclined shaft 20 between it and the gearing in the gear case 18. The shaft 20 is arranged to rotate in a pipe 21. The lower end of the pipe 21 is screwed into the gear case 18 to make a water-tight fit and is made water-tight at its upper end with the top sheet 22 of the tender by suitable packing 23. The shaft 20 is connected to the crank shaft of the engine 19 by gearing 24. Bracing 25 prevents the weight of the engine from sagging the top sheet 22.

To obtain the required speed of the conveyor screw 17 a series of gear reductions is inserted in the power transmitting mechanism between it and the engine, the gear 28 on the shaft 20 is larger than the pinion 29 on the crank shaft 30 of the engine, hence the gearing 24 reduces the speed between the engine 19 and the shaft 20. The bevel pinion 31 on the bottom of shaft 20 is smaller than the bevel gear 32 on the intermediate shaft 33 in the gear case, thus reducing the

speed between the inclined shaft 20 and the intermediate shaft 33. The pinion 34 on the intermediate shaft 33 drives the gear 35 on the shaft 36, which is secured to and rotates the conveyor screw 17. Near the bottom of the gear case is a shaft 37 having a gear 38 thereon in mesh with the intermediate pinion 34. Coupled to the short shaft 37 is a rigid shaft 39 extending along the under side of the transfer conduit 10, the full length of the conduit. The shaft 39 is also provided with a water-tight casing in a manner similar to that previously described; that is, by having it rotate in a pipe 40, which is screwed in the gear case 18 at its rear end 41 to make a water-tight fit and is welded, at its forward end 42, to the transfer conduit making a water-tight joint. The shaft 39 is universally jointed at 43 to a shaft 44. The shaft 44 comprises the two telescopic sections 45 and 46. The shaft 44 is universally jointed at 47 directly to the elevator screw 48. It is necessary to have the shaft 44 flexibly mounted and telescopically extensible to provide for the relative movement of the locomotive with the tender as they travel on curves. The rear end of the screw 48 is provided with a spherically shaped disc 49 which rotates and fits snugly in the spherically shaped socket 50 at the bottom of the elevator conduit 11, and prevents coal from leaking out of the conduit around the universal joint 47. This disc 49 constitutes the sole journal of the screw 48 at its driven end and forms with the socket 50 the sole bearing means for the screw 48 at its driven end.

I have found by making layouts on numerous locomotives that in order to obtain enough space to insert the spout 12 between the transfer conduit 10 and the elevator conduit 11 and make a practical construction, it is necessary to provide a rearwardly offset recess 51 at the forward end 40 of the transfer conduit and have the flexible connection between the spout and transfer conduit in the recess. If this flexible connection were forward of the recess there would not be sufficient space to insert the spout. The recess 51 is formed by the flange 52 which extends outwardly from the transfer conduit near the forward end thereof, the forwardly extending flange 53, and the outwardly extending flange 14 which is riveted to the front sheet 16. The transfer conduit 10 and the flanges 52, 53 and 14 are all cast integral, thus numerous water-tight connections are unnecessary.

The spout 12 is attached to the transfer conduit by a vertical pivot pin 55. Loose contact at the pivot 55 permits slight vertical movement of the spout. It will be noted in Figures 5 and 6 of the drawings that the plan view of the flexible connection 54 between the spout and transfer conduit is somewhat of a ball and socket joint in order that the spout may swing transversely.

The rear end of the elevator conduit 11 is open at its top to receive fuel downwardly from the spout 12. The spout is supported at its forward end on the rearwardly extending flange 56 of the elevator conduit, and it is arranged to slide longitudinally and laterally on this flange as the locomotive negotiates curves. The sides 57 and 58 of the elevator conduit (Fig. 8) slope outwardly providing clearance 59 at each side of the spout between the spout and the sides, to allow lateral movement of the spout on the flange 56. The pivoted connection between the spout and transfer conduit is substantially in vertical alignment with the universal joint 43 and the slidable contact between the spout and elevator

conduit is substantially in vertical alignment with the universal joint 47 to make a neat and practical construction. In Figure 9 it will be seen that the cross-sectional shape of the spout at its rear end is square, and in Figure 8 it will be seen that the cross-sectional shape at the forward end is rectangular. By having the width of the spout at the forward end greater than the height installations can be made on many types of locomotives without greatly raising the height of 10 the decks.

In operation, the coal falls from the bunker 8 into the transfer conduit 10. The screw 17 conveys it through the transfer conduit and the rear portion of the spout 12 and forces it through the remainder of the spout where it falls by gravity into the rear of the elevator conduit 11, which is immediately beneath the forward end of the spout. The elevating screw 48 delivers the coal to the horizontal firedoor conduit 60 and forces it through the conduit 60 to the scattering table 61 from which it is discharged over the grates 4 by fluid jets (not shown). Making the part of the stoker at the firing opening 3 horizontal and forcing the fuel therethrough by the elevator screw 48, instead of conveying it directly to the scattering table 61 permits the use of a smaller firing opening. The sides 62 of the conduit 60 prevent coal from coming in contact with the sides of the firing opening. The forward parts 63 of the sides 62 can be hinged, and controlled by the fireman, to vary the positioning of the coal on the table 61 from one side to the other to obtain a level fire.

As the locomotive travels on a curve the relative movement between the locomotive and tender is partly compensated by the flexible connection 54 between the spout and transfer conduit and partly by the lateral movement of the spout on the elevator conduit.

The novel combination and arrangement in the tender, of the fuel and water sections thereof with the tender unit of the stoker, and especially that feature which contemplates the mounting of the stoker driving mechanism rearward of the stoker trough and operatively connecting the stoker fuel advancing means with the driving mechanism by means which extends through the water section, described herein and shown by the drawings herewith, has been made the subject matter of divisional application Serial No. 599,725, filed March 18, 1932.

Having now described my invention, what I claim as new and desire to secure by Letters Patent, is:

1. In a locomotive having a tender and a back-head provided with a firing opening; a stoker comprising a transfer conduit rigidly mounted on the tender, an elevator conduit rigidly mounted on the locomotive in communication with said opening, an intermediate conduit flexibly connected to said transfer conduit, the forward end of said intermediate conduit being above and extending to the rear end of said elevator conduit, gearing at the rear end of said transfer conduit, a screw in said elevator conduit, said screw being connected to said gearing by a rotatable sectional shaft extending along the underside of said intermediate conduit and said transfer conduit, the section of said shaft beneath the transfer conduit being fixed against movement laterally of the tender and the shaft section beneath said intermediate conduit comprising two telescopic extensible and contractible parts, a universal joint connecting the first named section with the

rear part of the second named section, and a universal joint directly connecting the forward part of the second section with the elevator screw.

5 2. In a locomotive having a tender and a back-head provided with a firing opening; a stoker comprising a transfer conduit rigidly mounted on the tender, an elevator conduit rigidly mounted on the locomotive in communication with said opening, an intermediate conduit flexibly connected to said transfer conduit, the forward end of said intermediate conduit being above the rear end of said elevator conduit and having slidable contact therewith, gearing at the rear of said transfer conduit, a screw in said elevator conduit, said screw being connected to said gearing by a rotatable shaft extending along the underside of said intermediate conduit and said transfer conduit, the section of the shaft beneath the transfer conduit being fixed against movement laterally of the tender and the shaft section beneath said intermediate conduit comprising two telescopic parts, a universal joint connecting the first named section with the rear part of the second named section, and a universal joint directly connecting the forward part of the second named section with said elevator screw, said transfer conduit, the elevator conduit, the intermediate conduit and the rotatable shaft all being disposed on the longitudinal median line of the locomotive and tender.

3. In a locomotive having a tender and a firebox, a stoker comprising a conduit rigidly mounted on the tender, a conduit rigidly mounted on the locomotive in communication with the firebox, a spout flexibly connected in end to end relation with the first named conduit and arranged to move universally therewith, the forward end of said spout being immediately above and extending to the rear end of the second named conduit, the width of the forward end of said spout being greater than the height and the sidewalls of the spout diverging outwardly from the rear to the front thereof, and conveyor screws in said stoker for delivering the fuel therethrough.

4. In a locomotive having a tender and a firebox; a stoker comprising a conduit rigidly mounted in the tender, a conduit rigidly mounted in the locomotive in communication with the firebox, a spout flexibly connected to the first named conduit, the forward end of said spout being immediately above the rear end of the second named conduit, the cross-sectional shape at the rear of said spout being substantially square, the height of the forward end of said spout being less than the height of said rearward portion and the width of said forward end being greater than its height, and conveyor screws in said stoker for delivering the fuel therethrough.

5. In combination, a locomotive having a back-head provided with a firing opening, a tender for said locomotive, an elevator conduit mounted on said locomotive and extending forwardly and upwardly toward said firing opening, means for transferring fuel from said tender to said elevator conduit, the lower end of said elevator conduit being offset from the discharge end of said fuel transferring means, a screw conveyor in said elevator conduit receiving fuel from said means, the lower end of said elevator conduit provided with a spherical portion and the lower end only of said screw conveyor being provided with a spherical member seated in said spherical portion, said spherical portion constituting the

sole bearing for said conveyor screw at its lower end and one element of a flexible drive connection extending directly from the spherical member of said screw outwardly of the conduit through its spherical portion.

6. In combination, a locomotive having a back-head provided with a firing opening, a tender for said locomotive, an elevator conduit mounted on said locomotive and extending forwardly and upwardly toward said firing opening, means for transferring fuel from said tender to said elevator conduit, the lower end of said elevator conduit being disposed immediately below the discharge end of said fuel transferring means, a screw conveyor in said elevator conduit receiving fuel from said means, the lower end of said elevator conduit provided with a spherical portion and the lower end only of said screw conveyor being provided with a spherical member seated in said spherical portion, said spherical portion constituting the sole bearing for said conveyor screw at its lower end and one element of a flexible drive connection extending directly from the spherical member of said screw outwardly of the conduit through its spherical portion.

7. A conveying system comprising in combination a conduit having one end thereof provided with a spherical portion, and a screw conveyor rotatably mounted in said conduit, one end only of said screw conveyor being provided with a spherical member seated in the spherical portion of said conduit and one element of a flexible drive connection extending directly from the spherical member of said screw outwardly of the conduit through its spherical portion.

8. As an article of manufacture, a screw conveyor arranged to be driven from one of its ends, said driven end only being provided with a member having a spherical surface and one element of a flexible drive connection extending outwardly from the spherical surface of said member.

9. In a locomotive having a tender and a back-head provided with a firing opening; a stoker comprising a transfer conduit rigidly mounted on the tender, an elevator conduit rigidly mounted on the locomotive in communication with said opening, an intermediate conduit flexibly connected to said transfer conduit, the forward end of said intermediate conduit being offset from and extending to the rear end of said elevator conduit, gearing at the rear end of said transfer conduit, a screw in said elevator conduit, said screw being connected to said gearing by a rotatable sectional shaft extending along said intermediate conduit and said transfer conduit, the section of said shaft extending along the transfer conduit being fixed against movement laterally of the tender and the shaft section extending along said intermediate conduit comprising two telescopic extensible and contractible parts, a universal joint connecting the first named section with the rear part of the second named section, and a universal joint connecting the forward part of the second section with the elevator screw.

10. A conveying system comprising in combination a conduit having one end thereof provided with a spherical seat, and a screw floatably and rotatively mounted in said conduit, the shaft of said screw having a spherical surface at one end only, mating with and slidably contacting the spherical seat in said conduit to provide angular movement of said screw within said conduit, said spherical seat constituting the sole

bearing means for the spherical surface of said screw shaft.

11. A conveying system comprising in combination a conduit having one end thereof provided with a spherical seat, a screw floatably and rotatively mounted in said conduit, the shaft of said screw having a spherical surface at one end only, mating with and slidably contacting the spherical seat in said conduit to provide angular movement of said screw within said conduit, said spherical seat constituting the sole bearing means for the spherical surface of said screw shaft, and one element of a drive connection extending from the spherical surface of said shaft outwardly of the conduit through the spherical seat of said conduit.

12. A conveying system comprising in combination a conduit, a conveyor screw floatably and rotatively mounted in said conduit, a bearing carried by said conduit at one end thereof for one end of said conveyor screw, said bearing constituting the sole journaling means for

the shaft of said conveyor screw at the said one end of said screw, said bearing including a spherical surface forming a seat, and a member carried by one end only of the shaft of said conveyor screw having a mating spherical surface slidably contacting the spherical surface of said bearing to provide angular movement of said conveyor within said conduit.

13. As an article of manufacture, a screw conveyor having a shaft provided with a screw flight, one end only of said shaft being provided with a member having a spherical surface constituting the sole journal portion thereof.

14. As an article of manufacture, a screw conveyor having a shaft provided with a screw flight, flight, one end only of said shaft being provided with a member having a spherical surface constituting the sole journal portion thereof and one element of a flexible drive connection extending outwardly from the spherical surface of said member.

NATHAN M. LOWER.
